BURIAL VAULT

Thomas R. Herbest, Jr., Wheeling, W. Va., assignor to The Consolidated Expanded Metal Companies, Wheeling, W. Va., a corporation of West Virginia

Application May 17, 1933, Serial No. 671,423

15 Claims. (Cl. 72—7)

This invention relates to burial vaults or similar structures and a method of manufacturing the same. Furthermore, the invention is especially concerned with the type of vault which is adapted to be positioned in the grave and receive a coffin or casket.

Burial vaults of this type are ordinarily made in three or four substantially standard sizes and their walls are usually formed from concrete or the like moulded about metallic reenforcement.

The primary object of the present invention is involved in the simplification of the reenforcement pieces and the arrangement thereof in a novel manner whereby pieces of the same dimensions may be employed in the construction of vaults of any one of a plurality of the different standard sizes.

Other objects and advantages of the invention will appear more fully as this description proceeds.

How the foregoing and also the additional objects and advantages to be brought out herein-after are obtained will appear more fully from consideration of the following description making reference to the accompanying drawings, in which—

Figure 1 is a perspective view of a burial vault reenforcement assembly constructed in accordance with the present invention, the view having certain portions thereof broken away for the sake of clarity;

Figures 2 and 3 are cross sectional views illustrating the arrangement of the reinforcing elements which I prefer to employ in vaults of two different standard or predetermined sizes;

Figure 4 is a diagrammatic plan view of a sheet of reenforcement fabric which I prefer to employ;

Figure 5 is a perspective view of a templet or shaping part which is preferably employed in practicing the present invention; and

Figure 6 is a view of a part similar to that shown in Figure 5 but of different dimensions, this view also illustrating the manner of using the templet.

In referring to the drawings, reference is first made to Figure 1 which illustrates a number of fabric sheets suitably bent and assembled to form a unitary vault reenforcement in the manner now to be described. The two side walls and the bottom wall of the vault are formed from only two fabric or meshwork sheets, an example of one of which appears diagrammatically in Figure 4. This sheet, it will be observed, includes cross wires 9 which may be spaced from each other uniform distances throughout the length of the

sheet. The longitudinally extending wires or bars, however, are spaced from each other different distances at different points. At one edge (the top edge in Figure 4) the longitudinal wires 10—10 are positioned relatively close to each other while the next few wires 11 preferably have greater spacing. Toward the center of the sheet the longitudinal wires 12 are again relatively closely spaced, and the remainder of the sheet may be made up of wires 11 spaced from each other substantially the same distance as those of the same number referred to above.

In constructing the two side walls and the bottom wall of the vault from a pair of sheets such as shown in Figure 4, each sheet is bent approximately 90° along a line extended lengthwise of the sheet in the region of the closely spaced wires 12. By reference now to Figures 1 and 2 it will be seen that this bending operation results in the positioning of the closely spaced wires 10 adjacent the top edges of the side walls. It will further be apparent that the closely spaced wires 12 are located in and adjacent to the bottom corners of the side walls. As clearly seen in Figure 2, the inner edges of the two sheets overlap in a central region of the bottom wall, and it will therefore be apparent that extra reenforcement is afforded at the three points where it is most needed, i. e., in the middle of the bottom wall, at the bottom edges of the side walls, and at the top edges of the side walls.

At this time it is pointed out that the showing of Figure 2 represents the smaller of one of a group of substantially standard size vaults. The vault illustrated in Figure 3 is a slightly larger vault of substantially standard dimensions in which only the width of the vault has been increased over the dimensions of the vault of Figure 2. From comparison of Figures 2 and 3, however, it will be seen that the dimensions of the fabric sheets from which the side and bottom walls are formed are such that in both of these two standard size vaults the meshwork sheets overlap to some extent in the central region of the bottom wall. Sheets of the type shown in Figure 4, therefore, may be employed in forming reenforcement baskets for vaults of a plurality of different predetermined sizes. While, in Figures 2 and 3, the two vaults differ in width only, it will be understood that the mesh-work sheets may just as readily be employed in vaults of the same width but of different height or, for that matter, in vaults of different width and height.

The end walls for vaults of the dimensions of

those shown in Figures 2 and 3 may also, in a similar manner, be formed from meshwork sheets of the same size. By reference to Figures 1, 5 and 6, it will be seen that an end wall 5 reenforcement sheet may conveniently be formed of cross wires or bars 13 and upright wires 14, the spacing for which need not necessarily be different in different areas of the sheet, although I prefer to employ a sheet in which relatively 10 close spacing appears between two upright wires 14 in a central region, as clearly seen in Figures 1, 5 and 6. The purpose of this feature is increased strength in the center of the end walls.

In accordance with the preferred method of 15 fabricating the baskets, the end wall sheets are placed over forming members or templets such as shown at 15 and 15a in Figures 6 and 5, respectively. These members 15 and 15a are provided with angle members or hooks 15b and 20 15c, respectively, against which the upper edge 25 of an end wall meshwork sheet may abut when the sheet is to be bent or formed. The members 15 and 15a are further provided with grooves 13a and 14a located in the side edges and in the bottom edge, respectively, in order to receive the wires 13 and 14 when they are bent down over the edges of the templet in the manner clearly 30 appearing in Figure 6. Uniformity of bending from one piece to the next is therefore assured 35 since, if the workman always positions a sheet to be bent against the hook members 15b or 15c, the bending will take place at the proper lines for the particular vault under construction. The accurate bending of the end wall reenforcement 40 pieces provided in accordance with the foregoing is of considerable advantage in facilitating fabrication of the remaining portions of the vault, since these end wall pieces act as a framework to which the side pieces are rigidly tied, thereby 45 obtaining the exact and proper spacing between side wall members without recourse to laying these members out and measuring them to obtain the proper overlapping of the sheets.

From comparison of Figure 5 with Figure 6, 50 however, it will be seen that the member 15a is of slightly greater width than the member 15, this difference, of course, being employed for the purpose of forming end walls for vaults of different width. In accordance with the specific showing of the drawings, the forming member 15 is employed in shaping the end walls for a vault of the size illustrated in Figures 1 and 2, while the member 15a of Figure 5 is employed for a similar purpose in connection with a vault of the 55 width shown in Figure 3.

After placing a flat fabric sheet over one of the forming members in the manner clearly shown in Figure 7, the three projecting edges of the sheet are bent downwardly, by means of a hammer or the like, as a result of which the sheet takes the form of a dished reenforcement piece of the shape which clearly appears in Figure 1. These end walls and the side and bottom wall pieces may then be assembled, and it will be observed that, upon assembly, the upright corners between the side and end walls are reenforced by virtue of the overlapping of the bent portions of the end walls with the ends of the side walls. Similar reenforcement is provided 60 along the bottom corner between the end walls and the bottom wall.

After positioning or assembly of the several sheets forming the side, bottom and end walls, the concrete, of course, may be poured or moulded 65 around the reenforcement basket in the manner

clearly illustrated by the broken line showing x in Figures 2 and 3.

At this time it is also pointed out that one of the principal advantages of the present method and structure is that the reenforcement baskets are uniformly and accurately made so that a uniform positioning of the reenforcement in the concrete is readily obtainable. The arrangement of the reenforcing to provide extra reenforcement in certain zones and at certain edges 10 and corners also assures maximum strength with minimum of materials employed. It will be observed, furthermore, that even though pieces of uniform size are employed in the construction of reenforcement baskets for different size vaults, 15 the extra reenforcement is still located in the proper zones or at the proper corners, etc.

In considering the structure of the roof or cover for the vault, attention is first called to the showing of Figure 2 from which it will be 20 seen that the roof reenforcement is made from a pair of sheets of fabric, the various longitudinal wires 16 and cross wires 17 of which may all be of uniform spacing, the two sheets being positioned to overlap in the central region of the 25 roof. This overlapping again provides increased reenforcement in the region where it is most needed without, however, excessively increasing the thickness of the reenforcing elements, as a result of which the roof may also be constructed 30 of relatively thin concrete.

Similarly, the vault of Figure 3 has a roof or cover formed by means of fabric sheets which may be of exactly the same size as those employed in the roof of Figure 2. In this instance, 35 however, since the vault is slightly wider, the overlapping at the central region thereof is not quite as great as in the arrangement of Figure 2.

In connection with the formation of the various walls of the vault, it might be noted that while certain of the predetermined or standard vault sizes differ from each other only as to width or height of the vault, so that identical pieces may be employed in forming, for example, the side and bottom walls of such vaults, certain other vaults of standard or predetermined sizes may necessitate the use of longer meshwork sheets and, with this in mind, if desired, certain of the meshwork sheets may be made of 50 maximum length and cut down to the length of such vaults as have smaller lengthwise dimension.

Figures 1 to 3 inclusive illustrate a somewhat arched roof or cover construction and I prefer 55 to form the end portions of the roof reenforcement in a special way to be described in connection with Figure 1. As here shown a tapered portion is provided at each end of the vault roof and I prefer to construct the reenforcement 60 for the tapered end from a separate fabric piece having transverse wires 20 and wires 21 which are extended longitudinally of the vault. The wires 21 are bent at points 22 so that the end portions thereof extend in parallelism with the 65 longitudinal wires 17 of the main roof pieces. These end reenforcement pieces may be secured as by wiring indicated at 24, and it will be noted that by this arrangement a very rigid roof structure results without, however, unduly complicating the character of the several pieces employed or excessively multiplying their number.

From the foregoing it will be seen that reenforcement baskets for vaults may be constructed in accordance with my invention from a minimum 75

number of stock pieces even though the vaults may vary in certain of their dimensions. Extra reinforcement is also afforded at all those places which might be subjected to appreciable strains.

5 I claim:—

1. A meshwork sheet for reenforcing side and bottom walls of burial vaults or the like of different sizes within a predetermined range, said sheet being adapted to be bent in a region intermediate the edges thereof so that portions of the sheet extend in the plane of a side and in the plane of the bottom wall of the vault, and said sheet including reenforcement elements forming a network, the elements being spaced from each other relatively small distances in said intermediate region of the sheet as compared with the spacing of said elements in other areas thereof, the intermediate region of relatively close spacing being of sufficient width to provide increased reenforcement adjacent the corner formed by the bending operation when bending the sheet for purposes of reenforcement of side and bottom walls of any vault within said predetermined range, the size and rigidity of the elements of which the meshwork is composed being sufficient to provide a self-sustaining handleable unit when a plurality of the sheets are assembled in the form of a reinforcement basket for the vaults or the like.

30 2. A meshwork sheet for reenforcing side and bottom walls of burial vaults or the like of different sizes within a predetermined range, said sheet being adapted to be bent in a region intermediate the edges thereof so that portions of the sheet extend in the plane of a side and in the plane of the bottom wall of the vault, and said sheet including reenforcement elements forming a network, the elements being spaced from each other relatively small distances in said intermediate region of the sheet as compared with the spacing of said elements in other areas thereof, the intermediate region of relatively close spacing being of sufficient width to provide increased reenforcement adjacent the corner formed by the bending operation when bending the sheet for purposes of reenforcement of side and bottom walls of any vault within said predetermined range, and said sheet further being of such proportions that the portion thereof at one side of the line of bend is of sufficient dimension to extend substantially throughout the width of the wall in whose plane it is located and that the portion at the other side of the line of bend is of such dimension as to extend throughout only a fraction of the width of the wall in whose plane it is located, the size and rigidity of the elements of which the meshwork is composed being sufficient to provide a self-sustaining handleable unit when a plurality of the sheets are assembled in the form of a reinforcement basket for the vaults or the like.

3. A meshwork reinforcement sheet for burial vaults or the like of different sizes adapted to be bent along different lines in a central region thereof of predetermined width, so as to provide reinforcement in two adjoining walls of vaults of different sizes, said sheet being composed of a network of reinforcement elements of size and rigidity sufficient to provide a self-sustaining handleable unit when a plurality of the sheets are assembled in the form of a reinforcement basket for the vaults or the like, and the spacing of said elements being relatively small substantially throughout the width of said central region as compared with other areas of the sheet.

4. A meshwork reinforcement sheet for burial vaults or the like of different sizes adapted to be bent along different lines in a central region thereof of predetermined width, so as to provide reinforcement in two adjoining walls of vaults of different sizes, said sheet being composed of a network of reinforcement elements of size and rigidity sufficient to provide a self-sustaining handleable unit when a plurality of the sheets are assembled in the form of a reinforcement basket for the vaults or the like, the spacing of said elements being relatively small substantially throughout the width of said central region as compared with other areas of the sheet, and said elements further having small spacing in a region adjacent the edge of the sheet adapted to be used at the top of the vault body.

5. As an article of manufacture, a reinforcement structure for a separately handleable roof or cover of a burial vault or the like, said structure being composed of a plurality of meshwork reinforcement sheets integrated to form a unitary structure, the sheets being of uniform width and positioned to overlap each other in a central region of the roof or cover, and said sheets having sufficient strength and rigidity to form a self-sustaining handleable unit when assembled in the shape of the roof or cover.

6. As an article of manufacture, a reinforcement structure for a separately handleable roof or cover of a burial vault or the like, said structure being composed of a plurality of meshwork reinforcement sheets integrated to form a unitary structure, the sheets being of uniform width and positioned to overlap each other in a central region of the roof or cover, and the sheets further being bent downwardly toward the ends of the roof, and said sheets having sufficient strength and rigidity to form a self-sustaining handleable unit when assembled in the shape of the roof or cover.

7. As an article of manufacture, a reinforcement structure for burial vaults or the like including a plurality of network reinforcement sheets integrated to form a basket structure having a bottom, side and end walls, there being a pair of sheets having their edges overlapped in the region of the central longitudinal axis of said bottom wall, the sheets of said pair also being bent to lie in the planes of the side walls of the basket, and said sheets having sufficient strength and rigidity to form a self-sustaining handleable unit when assembled in basket form.

8. As an article of manufacture, a reinforcement structure for burial vaults or the like including a plurality of network reinforcement sheets integrated to form a basket structure having a bottom, side and end walls, there being a pair of sheets having their edges overlapped in the region of the central longitudinal axis of said bottom wall, and there being sheets having their edges overlapped at the upright corners between the side and end walls, and said sheets having sufficient strength and rigidity to form a self-sustaining handleable unit when assembled in basket form.

9. As an article of manufacture, a reinforcement structure for burial vaults or the like including a plurality of network reinforcement sheets integrated to form a basket structure having a bottom, side and end walls, there being a pair of sheets having their edges overlapped in the region of the central longitudinal axis of said bottom wall, and said sheets having sufficient strength and rigidity to form a self-sustaining handleable unit when assembled in basket form.

10. As an article of manufacture, a reinforcement structure for burial vaults or the like including a plurality of network reinforcement sheets integrated to form a basket structure having a bottom, side and end walls, there being sheets having their edges overlapped at corners between at least certain of said walls, and said sheets having sufficient strength and rigidity to form a self-sustaining handleable unit when assembled in basket form. 5
11. A reinforcement structure for burial vaults or the like including a pair of counterpart meshwork sheets forming the end walls of the structure and having edges thereof bent to lie in the planes of the side and bottom walls, and a pair of counterpart meshwork sheets each bent so as to define a side wall of the vault and a portion of the bottom wall thereof, said edges of the first pair being arranged in overlapping relation 10
- 15
16. A reinforcement structure for burial vaults or the like including a pair of counterpart meshwork sheets being integrated to form a unitary basket-like reinforcement structure and further being composed of wire or rod-like reinforcement elements arranged in crisscross formation having appreciable inherent rigidity or strength sufficient to permit handling of a completed basket as a unit, the second pair of sheets having edge portions thereof overlapping along the central longitudinal axis of the bottom wall. 20
17. A reinforcement structure for burial vaults or the like including a pair of counterpart meshwork sheets forming the end walls of the structure and having edges thereof bent to lie in the planes of the side and bottom walls, and a pair of counterpart meshwork sheets each bent so as to define a side wall of the vault and a portion of the bottom wall thereof, said edges of the first pair being arranged in overlapping relation 25
- 30
31. A reinforcement structure for burial vaults or the like including a pair of counterpart meshwork sheets being integrated to form a unitary basket-like reinforcement structure and further being composed of wire or rod-like reinforcement elements arranged in crisscross formation having appreciable inherent rigidity or strength sufficient to permit handling of a completed basket as a unit. 35
32. A reinforcement structure for burial vaults or the like including a pair of counterpart meshwork sheets forming the end walls of the structure and having edges thereof bent to lie in the planes of the side and bottom walls, and a pair of counterpart meshwork sheets each bent so as to define a side wall of the vault and a portion of the bottom wall thereof, said edges of the first pair being arranged in overlapping relation
- with reference to the end portions of the sheets lying in the side and bottom walls, said meshwork sheets being integrated to form a unitary basket-like reinforcement structure and further being composed of wire or rod-like reinforcement elements arranged in crisscross formation having appreciable inherent rigidity or strength sufficient to permit handling of a completed basket as a unit. 5
13. The method of constructing a meshwork reinforcement structure for a burial vault or the like which includes bending a meshwork sheet so that portions thereof lie in the planes of an end wall and a side wall of the vault, and forming an additional meshwork sheet to lie 10 in the planes of said side wall and the bottom wall of the vault by bending the second sheet in conformity with the width of the side wall as determined by the bending of the first sheet. 15
14. The method of constructing a meshwork reinforcement structure for a burial vault or the like which includes bending a meshwork sheet so that portions thereof lie in the planes of two walls of the vault, bending an additional sheet to lie in the planes of two walls one of which is 20 different from the planes of the first two walls, and utilizing the sheet first bent as a gauge for the bending of the second sheet. 25
15. As an article of manufacture, a sheet of meshwork reinforcing material for combined 30 side wall and corner construction, said sheet having an intermediate portion where the mesh is relatively fine and within the region of which the sheet may be bent at any one of a plurality of points, and said sheet having the portions at 35 each side of said midportion of a mesh which is relatively coarse.

THOS. R. HERBEST, JR.
